UNITED STATES PATENT OFFICE.

HERMAN MEYER, OF SALT LAKE CITY, UTAH.

BLACKBOARD-ERASER CLEANER.

No. 846,681.

Specification of Letters Patent.

Patented March 12, 1907.

Application filed February 10, 1906. Serial No. 300,541.

To all whom it may concern:

Be it known that I, HERMAN MEYER, a citizen of the United States, residing at Salt Lake City, in the county of Salt Lake and State of Utah, have invented new and useful Improvements in Blackboard-Eraser Cleaners, of which the following is a specification.

The object of this invention is to provide means in a cheap and durable form for removing quickly and effectively the chalk-dust from blackboard-erasers and to accomplish this end without allowing the dust to escape into the atmosphere. The dust being confined within the dust-chamber of the device will be deposited on the bottom and can be readily removed at desired intervals through an opening provided for that purpose.

The accompanying drawing illustrates the invention, its various parts being referred to by letters, similar letters denoting corresponding parts in the several views.

In the drawing, Figure 1 is a fragmentary vertical section on line $x-x$ of Fig. 2 and with an eraser thereon in position to be cleaned. Fig. 2 is a fragmentary plan view of the device without the eraser and partly in section. Fig. 3 is an end elevation with the door partly opened.

The letter a designates the body of the device, having the dust-chamber a' . The top b of this chamber is set slightly below the upper edges of the sides of the body a . Grooves c are formed in the projecting sides of the body just above the top b . A slide made in two sections d and d' is provided with lateral wires e , or an equivalent, which move in the grooves c as the slide is operated. This slide has an opening d^2 intermediate of its ends to receive the eraser m .

An opening f is made through the top b into the dust-chamber a' . This opening is approximately the same size as the one in the slide and is covered with a screen g .

h is an exit for the chalk-dust and is preferably made at an end of the chamber a' . The upper edge of this exit has a cleat or guide i extending its entire length, and its lower edge has a short cleat i' , which permits a free passage of the dust from the chamber floor. j is a door for said exit, having groove j' , adapted to engage the guides i i' when closed.

l are hangers attached to the sides of the body, by which it is supported in the desired location.

The device is operated by placing the dusty eraser in the opening d^2 of the slide and then moving it back and forth over the screen g . The body should be long enough to permit the eraser to be moved along until it has nearly or quite cleared the screen, and one section of the slide should be long enough to cover the screen when the eraser is removed, so as to prevent the escape of dust from the chamber.

What I claim, and desire to secure, is—

1. A blackboard-eraser cleaner comprising a body having a dust-chamber provided with a top opening, a screen over said opening, and a slide having an opening intermediate of its ends and adapted to be reciprocated upon said screen as described.

2. A blackboard-eraser cleaner comprising a body having a dust-chamber therein provided with a top opening, a screen over said opening, lateral grooves in the sides of said body which project above its top, a slide having lateral guides to engage said grooves and an opening in said slide to permit an eraser to be reciprocated upon said screen as specified.

In testimony whereof I affix my signature in presence of two subscribing witnesses.

HERMAN MEYER.
